PROCESS AND APPARATUS FOR DEWAXING OIL

Filed Dec. 5, 1933

UNITED STATES PATENT OFFICE

2,067,162

PROCESS AND APPARATUS FOR
DEWAXING OIL

Harmon F. Fisher and Blair G. Aldridge, Los Angeles, Calif., assignors to Union Oil Company of California, Los Angeles, Calif., a corporation of California

Application December 5, 1933, Serial No. 700,996

7 Claims. (Cl. 204—24)

The invention relates to the separation of wax from wax-bearing oil. The invention relates more particularly to the electrical separation of suspensions of precipitated wax from oil. This 5 application is a continuation in part of application Serial No. 692,724 filed Oct. 9, 1933.

Crude oils from which lubricating oil is produced in many cases contains paraffin or wax which is carried over and remains in the lubricating oil distillate fractions derived therefrom. 10 If the temperature of these lubricating oil fractions containing wax or paraffin is sufficiently lowered wax or paraffin is found to begin to be precipitated from solution therein in the form 15 of a colloidal suspension and if the temperature is continued to be further lowered more wax is found to be precipitated until the resulting oil and wax mixture finally congeals to a semi-plastic or solid mass. Lubricating oil fractions containing 20 relatively large quantities of wax have relatively high congealing temperatures while oils containing small quantities of wax have correspondingly lowered congealing temperatures. Thus it is apparent that the presence of wax limits the 25 minimum temperature at which lubricating oils containing it can be used. The pour point of lubricating oil is that temperature 5° F. above the temperature at which the oil under certain specified conditions congeals or ceases to flow and it 30 is apparent, according to the conditions stated hereinabove, that the presence of wax or paraffin in lubricating oil largely governs this characteristic of the oil. Therefore, in the production of lubricating oil it is necessary to remove a large 35 portion of the wax or paraffin in order to lower its pour point and thereby extend the lower ranges of temperatures at which it retains its fluidity and lubricating qualities.

The separation of wax or paraffin from lubricating oil may be accomplished by a number of processes, two of the most common ones of which are the "cold settling process" and the "cold pressing process".

In the "cold settling process" the wax-bearing 45 oil may be first diluted with a quantity of a light hydrocarbon, such as liquid propane, naphtha, gasoline or kerosene. The diluted wax-bearing oil is slowly chilled by suitable refrigerating means for a period of 20 to 50 hours until a lowered 50 temperature is reached at which a substantial portion of wax is precipitated. The chilled oil and precipitate mixture is then allowed to stand for a period which may be as long as several weeks to allow the wax to settle to the bottom of the 55 chilling tank.

In the "cold pressing process" the diluted wax-bearing oil is chilled slowly, as in the hereinbefore described "cold settling process". Following this the resulting chilled mixture of precipitated wax and oil is pumped through a filter press at a high 5 pressure. The wax precipitate is collected upon the filter and the oil is removed as a pressed distillate relatively free from wax.

The objections to these processes are the necessarily high cost of refrigeration for the long 10 periods of time, the large outlay of chilling tanks and storage equipment required and the poor separation of oil and wax obtained. Moreover, amorphous and/or micro-crystalline wax has been found extremely difficult if not impracticable 15 to separate by the common filtration methods.

Objects of this invention, therefore, are to provide a method and apparatus for dewaxing oil wherein a substantial reduction of the length of time required for chilling the wax-bearing oil may 20 be accomplished and wherein the attendant outlay of refrigerating equipment may be substantially reduced. Objects of this invention are, moreover, to provide a process and apparatus for dewaxing oil wherein the conventional, slow 25 batch chilling method can be replaced by a method employing continuous rapid cooling such as those known as "flash chilling" and "shock chilling" which may include quick chilling resultant upon rapid evaporation of a freely volatile solvent 30 under a quick pressure drop, or quick chilling in cooling coils shock chilling; wherein the costly chilling tanks can be eliminated, and wherein a complete and satisfactory separation of wax can be effected by subsequent conventional separation 35 methods notwithstanding. Other objects of this invention are to provide a method and apparatus for electrically treating wax-bearing oil whereby filtration and/or settling operations are improved.

In general these objects are attained according 40 to the invention through "shock chilling" the wax bearing oil containing the diluent to precipitate wax from solution, subjecting the mixture of wax precipitate and oil thus formed to an intense electric field between electrodes adapted 45 to be self-cleaning and subsequently separating the wax from the oil by settling and/or filtering the said electrically treated oil-precipitate mixture.

It has been found that the disadvantages inherent in the common methods of wax separation 50 may be overcome by the process which will be described hereinafter. We have discovered that a wax precipitate in suspension in oil can be rendered more readily filtered or separated 55

by settling, by subjecting it to an intense electric field between electrodes which normally tend to become coated with deposited wax but which are inherently, or by reason of structure, self-cleaning. This type of electrode we have denoted as the "self-cleaning" or "agglomerating" type. In the usual mode of operation according to this invention, wax-bearing oils may be mixed with suitable diluents, the resulting solution chilled to a temperature at which wax precipitates from solution, the resulting mixture of wax-bearing oil, diluent and precipitated wax subjected to an intense electric field between self-cleaning or agglomerating type electrodes and the thus treated oil and precipitate mixture subsequently filtered. It has been found that the wax precipitate thus subjected to the electric treatment is agglomerated and/or otherwise modified in form and/or conditioned to be more readily filtered. It has also been discovered that an oil containing wax precipitate formed by "shock chilling" and subsequently electrically treated between self-cleaning electrodes, as hereinbefore described, can be filtered as readily as an oil containing wax precipitate which has been formed by the method of batch chilling alone. The effectiveness of the electrical treating in aiding filtration is particularly apparent in view of the fact that the same "shock chilled" wax-bearing oil is practically non-filterable prior to the said electric treatment. The wax-bearing oil containing precipitated wax formed by "shock chilling" is of such a fine texture and possesses such characteristics that it renders ordinary filtration operations impractical by plugging the filter leaves. The same "shock chilled" oil, containing wax precipitate, upon being electrically treated, between self-cleaning electrodes is agglomerated and/or otherwise modified to a form which is filterable by ordinary methods.

It has also been discovered that by electrically treating the wax-bearing oil containing wax precipitate according to the hereinbefore described process, the wax is rendered more readily settled, and in some cases the settling stage is employed subsequent to the electric treating either alone or prior to filtering to separate the wax precipitate from the oil. The diluent may be recovered by distillation subsequent to the separation of the wax from the solution according to the processes described hereinbefore.

Refrigeration of the wax-bearing oil-diluent solution may be accomplished either by means of external indirect heat exchange with a refrigerant prior to electrical treating or by direct cooling by means of evaporation of a normally gaseous liquid diluent from the wax-bearing oil solution prior to or during electrical treating. This refrigeration is preferably rapid but batch chilling over a relatively long period of time may also be employed in connection with electric treating with corresponding benefit in efficiency of settling and/or filtration.

It has been found that ordinarily in an electric treater employing conventional type electrodes a large proportion of the precipitated wax is removed from the wax-bearing oil-precipitate mixture in the form of a deposit or plate upon the electrodes between which the treating field is maintained. After a short period of electric treating the electrodes upon which the wax is deposited become thickly coated and it is necessary that this wax coat be continuously removed in order to maintain the apparatus in operative condition. This is particularly true where the

electric treating is employed entirely in connection with a settling or filtering process. If the wax is allowed to accumulate on the electrodes to a very great thickness it impairs the electric treating and agglomerating action and reduces the cross-sectional area between the electrodes through which the oil undergoing treatment flows. This reduction of cross-sectional area of treating space results in either a decrease in thoroughness in the treating or a substantial reduction in the capacity of the treater. The means heretofore employed for removing deposited wax from the electrodes has been in the form of scrapers. We have discovered that the preferred method of operation in connection with settling and filtration is to employ an electric treater incorporating an electrode design which is self-cleaning in action. The well known phenomenon of "electric windage" has been employed in the construction to maintain the electrodes free of wax. Any number of electrode structures may be employed to accomplish this but the preferable construction is that disclosed in patent application Serial No. 692,724.

The treater comprises in brief a gas tight shell in which is located a pair or plurality of electrodes adapted to contact the wax-bearing oil to be treated. Each pair of said electrodes is constructed to have a high effective area ratio with respect to one another. It has been found that where two oppositely charged electrodes of unequal area are placed in electrostatic relation to one another, that the fluid surrounding or in contact therewith is caused to flow in a rapidly moving stream from the electrode of smallest area to the electrode of largest area. This phenomena is taken advantage of in the construction of the present treater and as just stated hereinbefore the electrodes therein are constructed to have a high ratio of effective area.

The preferable construction, as illustrated in the drawing, comprises an outer cylindrical electrode and an inner electrode consisting of a series of conical elements axially positioned within the said cylindrical electrode. In operation currents of rapidly moving oil containing precipitated wax are found to flow downward and outward from the edges of the cones of the inner electrode and to impinge upon the inside surface of the outside cylindrical electrode. These currents are of sufficient intensity to wash or erode from this electrode surface any wax which tends to be deposited thereon. The wax particles of the wax precipitate in the chilled oil are in a majority of cases negatively charged and, therefore, tend to be deposited on the positively charged electrode only. Therefore, by maintaining the outside cylindrical electrode positively charged the tendency of wax deposition is confined to this electrode and no special means is, therefore, necessary to maintain the inner or negatively charged electrode free from wax. In some cases where the charges on the precipitated wax particles are found to be of different polarity, the polarity of the electrodes may obviously be reversed as required to cause the deposition of the wax to tend to take place on the electrode from which it is being continuously removed by the "windage" currents.

The invention broadly stated comprises a method of treating wax-bearing oil with an electric field or current between self-cleaning or agglomerating type of electrodes to aid separation of wax therefrom.

The invention more specifically stated com-

prises a process and apparatus for treating wax-bearing oil and/or wax-bearing oil containing precipitated wax in suspension wherein the said wax-bearing oil and/or the wax-bearing oil containing precipitated wax in suspension is subjected to an electric field or current between self-cleaning or agglomerating type electrodes to agglomerate or modify the precipitated wax, and wherein the said precipitated wax thus treated is subsequently separated from the oil by filtration. The invention also comprises a process for treating wax-bearing oil and/or wax-bearing oil containing precipitated wax in suspension wherein the said mixtures are subjected to an electric field or current between self-cleaning or agglomerating type electrodes to agglomerate and/or otherwise modify the wax precipitate to aid subsequent separation by settling methods. The invention also resides in a process for dewaxing oil wherein "shock chilled" wax-bearing oil is subjected to an electric field between self-cleaning or agglomerating type electrodes to render the wax precipitate thus formed readily separable by filtration or settling methods.

Other objects and advantages and features of the invention will be evident hereinafter.

The accompanying drawing illustrates one embodiment of the invention in which 10 is a storage tank to contain a supply of wax-bearing oil to be treated. Numeral 11 indicates a pressure storage tank for containing a diluent, such as liquid propane to be added to the wax-bearing oil. An interchanger or refrigerator for indirectly chilling the wax-bearing oil-diluent solution is illustrated at 20. A chilling tank 32 is provided in which the wax-bearing oil-diluent solution may be allowed to accumulate and in which the normally gaseous diluent, when such a diluent is employed, may be allowed to evaporate at reduced pressure to accomplish refrigeration of the said wax-bearing oil. The treater comprises a gas tight cylinder 40 having a spherical head 41 and a conical bottom 42 and containing a pair of electrodes 43 and 44. The electrode system comprises an outer cylindrical electrode 43 and an inner axially positioned electrode consisting of a series of superimposed hollow sheet metal cones 45 supported by rod 46 and lead-in insulator bushing 47. These cones 45 thus offer thin edges or points in opposition to the surface of the cylindrical electrode 43, which structure is conducive to the formation of electric windage currents between these cone edges and said surface of the cylinder 43 when the electrodes are charged to a high potential difference. A wax pump 50 is provided at the apex of the inverted conical bottom 42 by means of which settling may be ejected through line 51. A high electric potential is maintained between the electrodes 43 and 44 by means of a high potential generator 55 making connection to the inner electrode 44 through electrical conductor 56, lead-in insulator 47 and rod 46 and completing the circuit to the outer electrode 43 through the electrical conductor 57 and the metallic treater body.

A settling chamber 70 is provided in connection with the electric treater into which the electrically treated oil containing precipitated wax may be introduced for settling and separating the wax. Wax pump 71 is provided at the bottom thereof by means of which settling may be ejected through line 72.

A filter 80 of any suitable design is employed, preferably in direct connection with the electric treater through which the electrically treated oil

containing precipitated wax may be filtered to separate the wax from the oil. Wax is periodically removed from the filter through line 81. A pump 64 serves to supply the necessary oil pressure to the filter 80.

A still 90 is provided to receive the oil filtrate or decantate containing solvent. Solvent is evaporated and separated from the oil in still 90 by means of heat supplied through heating coil 91. A cooler 92 is provided on the bottoms outlet from the still 90 and a storage tank 95 into which is delivered the dewaxed oil from the bottoms of the still. A cooler 100 is provided in the vapor return line from the still and chiller. A pump 99 is provided for compressing vapors prior to cooling and a pump 101 is provided for returning condensate to the diluent storage tank.

The operation is as follows: Wax-bearing oil at a temperature above that at which wax is precipitated from solution is pumped from tank 10 by means of pump 17 through line 15 and valve 16 to mixer 14 where it meets a stream of solvent flowing from storage tank 11 through line 12 and valve 13. The ratio of wax-bearing oil to diluent meeting and dissolving in one another at mixer 14 is governed by regulation of the valves 13 and 16. The solution of wax bearing oil and solvent flows from mixer 14 through the refrigerator 20 where it passes in indirect heat exchange with a suitable refrigerant to reduce its temperature to a point where wax precipitate forms. The thus cooled wax-bearing oil containing wax precipitate after passing through refrigerator 20 is withdrawn and may flow through lines 21 and 24, valve 25, lines 26 and 27, pump 28 and inlet 29 to the electric treater.

In some cases instead of chilling the wax-bearing oil by indirect heat exchange with a refrigerant in a refrigerator, as illustrated here at 20, the wax-bearing oil is allowed to flow through the refrigerator 20 which is rendered inoperative by cutting off the supply of refrigerant thereto and passes therefrom through lines 21, 22 and valve 23 into the chilling tank 32. In this case valve 25 will be closed while valve 23 is opened. Self-refrigeration of the wax-bearing oil-diluent solution contained in and flowing through the chilling tank 32 is then accomplished by evaporation of a portion of the diluent therein at reduced pressure. The necessary reduction in pressure is accomplished by means of pump 99 which exhausts vapors formed in the chilling tank 32 through vapor outlet 33, valve 34 and line 35. Regulation of the pressure on the vapors in the chilling tank 32 is accomplished by adjustment of valves 34 and 98.

The wax-bearing oil-diluent solution containing precipitated wax after refrigeration in chilling tank 32, as hereinabove described, is withdrawn from the bottom thereof through valve 30 and lines 31 and 27 and forced by means of pump 28 through inlet 29 into the electric treater.

The chilled wax-bearing oil after entering the electric treater through inlet 29, passes downward therein between the electrodes 43 and 44 where it is subjected to an intense electric field. After being electrically treated between the electrodes 43 and 44 the wax-bearing oil flows out of the electrode system and into the space 48 inside of the treater shell 40 surrounding the electrode system. A small portion of the wax precipitate in the thus electrically treated wax-bearing oil may settle to the bottom of the treater and any such settling, when sufficient quantity

has accumulated, are withdrawn and ejected through line 51 by means of wax pump 50.

The oil-diluent solution containing most of the electrically treated precipitated wax moves upward in the space 48 in the treater and is withdrawn through outlet 58 near the top thereof. A pressure is maintained in the electric treater by means of pump 28 sufficient to prevent ebullition therein of the oil-diluent solution which would be detrimental to the electric treating and settling operations.

The oil-diluent solution containing electrically treated precipitated wax which is withdrawn from the treater through outlet 58 may pass through valve 59, lines 62 and 63 and be forced by means of pump 64 through line 65, valve 66 and connection 67 through the filter press 80. The oil-diluent solution from which the electrically treated wax precipitate has been removed in filter press 80 continues in flow through the filter outlet connection 82 and inlet connection 83 into the still 90 where separation of the oil and diluent is caused to take place by means of the application of heat through heating coil 91. The wax removed from the oil in the filter press 80 is periodically ejected through wax outlet 81.

The still bottoms comprising the desirable oil fractions from which the solvent has been stripped is withdrawn through cooler 92 and delivered through line 94 to the dewaxed oil storage tank 95.

The diluent vapors stripped from the dewaxed oil fractions in still 90 are withdrawn from the top thereof through vapor line 96 and after passing through valve 98 are compressed along with other diluent vapors issuing from the chilling tank 32 through lines 35 are compressed by means of compressor 99, cooled in cooler 100 and the resultant condensate returned by means of pump 101 to the diluent storage tank 11. In case the diluent employed in the process is normally liquid the vapors thereof issuing from the still may be condensed in the cooler 100 without previous compression and the condensate returned to the diluent storage tank 11 by means of pump 101. When such a non-volatile normally liquid diluent is employed refrigeration of the solution will obviously be accomplished entirely by indirect heat exchange with a refrigerant as in refrigerator 20.

In some cases it may be desirable to separate the wax from the electrically treated oil-diluent solution containing precipitated wax by settling and this may be accomplished by allowing the said treated material withdrawn from the electric treater through line 58 to flow through valve 60 and inlet 61 into the settling chamber 70, in this case valve 59 is closed. The wax removed from the oil in the settling tank 70 by means of settling, is ejected from the bottom thereof through line 72 by means of wax pump 71. The oil-diluent solution from which the wax has thus been removed by settling is withdrawn from the top of settling tank 70 through outlet 73, valve 74 and line 63 to pump 64 by which it is forced through line 65 and filter by-pass lines 84 and 85 and valve 86 into the still 90 through inlet 83. When operating in this manner without filtration, valve 66 is closed.

It is sometimes found advantageous to combine the hereinbefore described operations of settling and filtering wherein a portion of the wax is removed by settling in settling tank 70 and the remaining wax removed by filtration in filter 80. When it is desired to so operate the oil-diluent

solution withdrawn from the settling tank 70 is also passed through the filter 80 before reaching the still 90. When operating in this manner the filter by-pass valve 86 is closed and the valve 66 opened.

A high potential electric field is maintained in the treating zone between the cones 45 of the electrode 44 and the surface of the cylindrical electrode 43 by means of a suitable high voltage source, such as generator 55. The circuit through the generator 55 from the electrodes 43 and 44 is completed through rod 46, lead-in insulator bushing 47, conductors 56 and 57 and the metallic treater body.

The electric potential supply 55 may be adapted to supply either direct current, interrupted unidirectional current or alternating current. In general, it has been found advantageous to maintain a unidirectional potential between the electrodes either interrupted or continuous with the positive polarity on the outside electrode of largest area, as illustrated in the drawing. A potential gradient of 45,000 to 75,000 volts per inch has been found effective in treating the wax-bearing oil containing precipitated wax according to the method hereinbefore described.

The temperature of the wax-bearing oil is ordinarily reduced either in refrigerator 20 or chilling tank 32 to between -20 and -40° F. depending upon the pour point desired in the finished product. This temperature is maintained throughout the electric treating, settling and filtering operations.

The cooling rates of the contents of the chilling tank 32 may be governed by the rate of evacuation or withdrawal of vapors therefrom through valve 34 to obtain a range of cooling conditions varying from batch chilling to flash chilling. For example, if it is desired to batch chill or slowly chill the oil or oil-diluent solution to be electrically treated, the pressure upon the contents of the chilling tank is slowly reduced over the desired period of time and at the desired rate until the minimum desired temperature is attained, at which point the said contents are withdrawn and allowed to pass through the electric treater. On the other hand, if it is desired to quickly cool or "shock chill", the oil-diluent solution is allowed to continuously flash through valve 23 into the tank 32 which is maintained at reduced pressure. Cooling rates may also be governed over a wide range by manipulation of the interchanger 20.

Diluents which may be used for refrigeration are liquid propane, butane and methylchloride. It has also been found possible to cool the contents of the chiller and the electric treater chambers by mixtures therein of liquid sulphur dioxide or ammonia. Other diluents which may be employed to prevent congealing of the chilled wax-bearing oil are naphtha, gasoline, liquid propane, acetone and benzol, methyl chloride, halogenated hydrocarbons, such as monochloro difluoro methane, dichlorodifluoro methane, dichlorethylene, trichlorethylene, ethers or mixtures of ethers and alcohols and gas oil or other heavy oils including dewaxed lubricating oil fractions.

The self-cleaning or agglomerating type of electrode system as described and illustrated herein has been found to possess the ability, when charged to a high potential difference, to agglomerate or modify the form of the wax precipitate formed in wax-bearing oils, in such a manner that subsequent treatment by filtration to separate wax is greatly improved in effectiveness and

efficiency. This may be due to a tendency for the wax precipitate particles to be deposited and to accumulate in relatively large concretions or flocks upon the electrode of opposite polarity, before being detached by the force of the "electric windage" current in the liquid or it may be due to subjection of the precipitate to the extremely high potential gradients which are formed between electrodes, such as those illustrated herein, where

10 their effective area ratios are high. In any event, wax precipitates which when untreated immediately plug and render a filter inoperative are found to be readily filtered after being treated electrically according to the hereinbefore described process and apparatus.

As an example of the operation of this invention for dewaxing oil by filtration, a wax-containing Santa Fe Springs lubricating oil distillate was dissolved in 2.5 volumes of liquid propane at atmospheric temperature and the solution shock chilled to a temperature of -50° F. by flashing it into a chilling drum at reduced pressure. This flash chilled solution was fed to the electric treator at a rate such that the wax-bearing liquid solution remained in the electric treating field for a period of approximately one half hour. An average potential gradient of 75,000 volts per inch was maintained through the material being treated.

30 The thus electrically treated wax-bearing oil was run through a filter at a constant pressure of 50 pounds per square inch and filtration rates varying from 0.3 to 0.5 gallon per square foot per hour obtained over a number of experimental runs.

The same flash chilled wax-bearing solution without electrical treatment was run through the same filter and filtration rates varying from 0.07 to 0.19 gallon per square foot per hour were obtained.

40 It is apparent from these results that average filtration rates for the electrically treated solution under the same chilling and filtering conditions was three times as great as that for the untreated flash chilled solution. Pour points of the filtrates obtained throughout the tests varied from 0 to 10° F.

The process and apparatus is not to be limited to the specific structure, nor to the treatment of 50 oils for the removal of wax but they are applicable to the treatment of similar substances for the removal of asphaltenes, asphalt, petrolatum, sludges, finely divided solids and other substances and impurities both solid and plastic.

55 The foregoing is merely illustrative of one apparatus and process and the invention is not limited thereby but may include any process and apparatus which accomplishes the same within the scope of the invention.

60 We claim:

1. A process for dewaxing oils which comprises passing a stream of wax-bearing oil between a pair of oppositely charged electrodes, whereby wax particles agglomerate and certain of said 65 wax particles tend to migrate and deposit upon an electrode of one polarity, establishing an electric windage from the other electrode of opposite polarity toward the surface of said first named electrode of sufficient intensity to prevent permanent deposition of wax particles thereon.

2. A process for dewaxing oils which comprises passing a stream of wax-bearing oil between a pair of oppositely charged electrodes whereby wax 70 particles agglomerate and tend to migrate and deposit upon an electrode of one polarity, main-

taining an electric potential upon the other electrode of opposite polarity sufficiently high to establish a sufficient fluid disturbance in said stream of wax-bearing oil in the direction of the surface of said first named electrode to prevent permanent deposition of wax particles thereon. 5

3. A process for dewaxing oils which comprises chilling said oil to precipitate wax therein, passing a stream of said wax and oil between spaced oppositely charged electrodes whereby wax particles agglomerate and tend to migrate and to deposit upon electrodes of one polarity, maintaining an electric potential upon electrodes of opposite polarity to establish an electrical windage circulatory current in said oil in the direction of 15 said first named electrodes whereby wax particles accumulating upon said electrodes are removed by the erosive action of said circulatory currents, and withdrawing agglomerated wax and oil from said electric field in a direction substantially concurrent to said electrical windage. 20

4. A process for dewaxing oil which comprises passing a mixture of oil and wax between an electrode of one polarity having a relatively large surface and an electrode of opposite polarity having a relatively small surface, inducing an electric field between said electrodes whereby wax particles agglomerate and tend to deposit upon said electrode of relatively large surface, establishing an electric windage adjacent the surface 30 of said electrode of relatively small surface in the direction of said electrode of relatively large surface of sufficient intensity to dislodge wax depositing on said last named electrode. 25

5. A process for dewaxing oils which comprises passing a stream of wax-bearing oil between a pair of oppositely charged electrodes whereby wax particles agglomerate and certain of said wax particles tend to migrate and deposit upon an electrode of one polarity, establishing an electric windage from the other electrode of opposite polarity toward the surface of said first named electrode of sufficient intensity to prevent permanent deposition of wax particles thereon and filtering the thus agglomerated wax from the oil. 45

6. A process for dewaxing oils which comprises chilling said oil to precipitate wax therein, passing a stream of said wax and oil between spaced oppositely charged electrodes whereby wax particles agglomerate and tend to migrate and to deposit upon electrodes of one polarity, maintaining an electric potential upon electrodes of opposite polarity to establish an electrical windage circulatory current in said oil in the direction of 50 said first named electrodes whereby wax particles accumulating upon said electrodes are removed by erosive action of said circulatory currents, and filtering the thus agglomerated wax from the oil. 55

7. A process for dewaxing oil which comprises passing a mixture of oil and wax between an electrode of one polarity having a relatively large surface and an electrode of opposite polarity having a relatively small surface, inducing an electric field between said electrodes whereby wax 65 particles agglomerate and tend to deposit upon said electrode of relatively large surface, establishing an electric windage adjacent the surface of said electrode of relatively small surface in the direction of said electrode of relatively large surface of sufficient intensity to dislodge wax depositing on said last named electrode and filtering the thus agglomerated wax from the oil. 70
